UNITED STATES PATENT OFFICE

101,765

DESIGN FOR A REFRIGERATED DEVELOPING UNIT FOR X-RAY PHOTOGRAPHS

Arthur W. Buck, St. Louis, Mo., assignor to Buck X-Ograph Company, St. Louis, Mo., a corporation of Missouri

Application May 28, 1936, Serial No. 62,895

Term of patent 14 years

To all whom it may concern:

Be it known that I, Arthur W. Buck, a citizen of the United States, residing at St. Louis, State of Missouri, have invented a new, original, and ornamental Design for a Refrigerated Developing Unit for X-Ray Photographs, of which the following is a specification, reference being had to the accompanying drawing, forming part thereof.

The figure is a perspective view of a refrigerated developing unit for X-ray photographs showing my new design. The figure shows the front and one side of a refrigerating developing unit formed in accordance with my design, it being understood that the opposite side and rear of the unit are provided with lower panels having louvres in the same manner as the front and side shown in the drawing.

This developing unit is characterized by the fact that each face of the unit is divided into an

upper and a lower depressed panel, thus there are four upper and four lower depressed panels. The upper depressed panels are longer than the lower depressed panels and the lower panels are provided with three vertical groups of louvres on the front and back, and two vertical groups of louvres on the side panels. The upper front panel at its upper end is provided with a cross bar and the top of the unit is open and divided into three rectangular openings, the middle opening being relatively large and the smaller openings on each side of the larger opening being equal in area but less in area than the area of the larger opening.

I claim:

The ornamental design for a refrigerated developing unit for X-ray photographs, as shown and described.

ARTHUR W. BUCK.
